CLAIM

The ornamental design for a display screen or portion thereof with animated icon, as shown and described.

DESCRIPTION

FIG. 1 is the first image in a sequence for a display screen with animated icon showing my/our new design; and, FIG. 2 is the second image thereof.

The appearance of the animated icon transitions sequentially between the images shown in FIGS. 1 and 2. The process or period in which one image transitions to another forms no part of the claimed design.
